UNITED STATES PATENT OFFICE.

CHARLES M. PEARSALL, OF RIDGEWOOD, NEW JERSEY.

SPARK PLUG.

Application filed March 29, 1927. Serial No. 179,356.

This invention relates to a spark plug, and has for its primary object the arrangement in a unitary article of a spark construction and a device whereby the spark plug may be 5 partially or entirely short-circuited.

An object of the invention is the construction of a spark plug incorporating in its construction a movable contact element whereby the distance between the electrodes of the 10 spark plugs may be bridged.

Another object of the invention is the construction of a spark plug having a detachable contact element, by means of which the spark plug may be tested.

15 A feature of the invention is the simplified construction of the contact element and mode of connection to the spark plug proper.

With these and other objects in view, my invention will be better understood from a 20 description of the same when taken in connection with the accompanying drawing, wherein:

Figure 1 is a side elevation of a spark plug constructed in accordance with my invention, 25 showing the contact in operative position;

Figure 2 is a similar view with the contact in its other position;

Figure 3 is a top plan view;

Figure 4 is a vertical sectional view 30 through the contact;

Figure 5 is an enlarged fragmentary view of the lower portion of the contact.

Again referring to the drawing illustrating one of the many constructions of my invention, the numeral 1 designates the central electrode of the spark plug supported within the shell 2 forming the outer electrode. This outer electrode or shell 2 is provided with an annular series of inclined holes 3 for frictional engagement with the contact of a 35 special construction so as to not only reduce materially the cost of manufacture but to facilitate the operative association of the contact with the various electrodes of the 40 spark plug.

One manner of accomplishing this desired result is illustrated in the drawing as a strip 4 bent to have an intermediate off-set portion 5 and an annularly extending end portion 6 45 and a tang 7 at its upper end for arrange-

ment in a knob 8 of insulating material. The contact strip intermediate its off-set portion is provided with a flattened contact or contact surface 9 so disposed as to be capable of moving into engagement with the central electrode, as shown in Figure 1. To enable the contact strip to swing in the arc of a circle and to effectively hold the contact in position against vibration, the lower end 6 is split, as indicated at 10, to provide the 55 prongs 11, each provided with a cam wall 12 to facilitate the insertion of the end into the hole, and due to the expansible action of the prongs the frictional engagement between the prongs and the wall of the associated hole 60 will effectively hold the contact in any one of its adjusted positions and besides effectively prevent vibration of the device.

With the construction of spark plug as illustrated, it will be appreciated that the 70 plug can be very easily tested and short-circuited in such a manner that the location of the contact will not interfere with the proper functioning of the other parts of the engine to which the plug is attached. The 75 novel arrangement of the multiplicity of holes enables the contact to be arranged in its most convenient position to be manipulated.

Of course, it will be understood that the 80 device may be constructed in various other manners than illustrated, as the main feature of my invention is the combination of parts whereby a contact may be made a permanent part of the plug and arranged to be easily 85 manipulated into and out of contacting relation with both electrodes and, therefore, I do not desire to be limited in any manner except as set forth in the appended claims.

I claim:

1. A contact element for use with a spark plug having an outer electrode provided with a hole nearly parallel to the plug axis, said contact element having one end split for insertion into and adapted to have frictional 95 engagement with said hole, said element further having an offset portion adapted to engage the central electrode of the plug when the element is rotated within the hole associated therewith.

2. A contact element for use with a spark plug having an outer electrode provided with a hole nearly parallel to the plug axis, said contact element having one end split for insertion into and adapted to have frictional engagement with said hole, said element further having an offset portion adapted to

engage the central electrode of the plug when the element is rotated within the hole associated therewith, and an insulation knob secured to said element at the end opposite the slit for moving the element. 10

In testimony whereof I affix my signature.

CHARLES M. PEARSALL.
